BRASSIÈRE

John V. Hollar, East Orange, N. J., assignor to
 Vogue Mfg. Co., Newark, N. J., a corporation
 of New Jersey

Application March 16, 1935, Serial No. 11,406

4 Claims. (Cl. 2-42)

This invention relates to improvements in women's undergarments; and the invention has reference, more particularly, to a novel and improved construction of brassière.

5 The invention has for its principal object to provide a novel construction of brassière of the full-fashioned type which not only serves to enclose the wearer's breasts, but also to support and mould the same to firmly uplifted and rounded contours; to this end a novel relatively rigid but flexible supporting means is incorporated with the lower parts or hemispheres of the breast-receiving portions of the brassière, which, when the latter is put on by the wearer, will 10 underlie and flex transversely around the lower or under portions of the wearer's breasts with firm uplifting, rounding and supporting effect thereupon.

20 The invention has for a further object to provide in connection with the lower parts or hemispheres of the breast-receiving portions of the brassière, at the interior sides thereof, upwardly open pockets to not only removably receive the novel relatively rigid but flexible breast uplifting 25 and supporting means which is a feature of this invention, but to floatingly support the same so that it automatically adjusts itself to the wearer's bust without tendency to dig into the flesh or otherwise cause discomfort to the wearer.

30 The invention has for another object to provide the novel relatively rigid but flexible uplifting and supporting means hereinabove referred to in the form of an initially flat sheet of pyroxylin or any other or like material which possesses the 35 requisite flexibility and which is unaffected by moisture; such sheet having a curvilinear periphery of suitable outline, so as to avoid sharp corners or projections likely to irritate the wearer of the brassière with which said sheets are incorporated.

40 Other objects of this invention, not at this time more particularly enumerated, will be understood from the following detailed description of the same.

45 An illustrative embodiment of the invention is shown in the accompanying drawing, in which:—

Fig. 1 is a front elevation of the novel brassière structure according to this invention, as it appears when upon the person of the wearer; 50 Fig. 2 is an inside face view of the breast-receiving portions of the brassière, this view being drawn on an enlarged scale; Fig. 3 is a fragmentary vertical section, taken on line 3-3 in Fig. 2, but drawn upon a somewhat further enlarged 55 scale; and Fig. 4 is a face view of one of the

breast uplifting and supporting devices utilized in connection with the breast-receiving portions of the brassière.

Similar characters of reference are employed in the hereinabove described views, to indicate 5 corresponding parts.

Referring to the drawing, the brassière comprises a pair of breast-receiving portions, preferably of the full-fashioned type, the same being preferably connected together by an intermediate panel or diaphragm section 5 stitched or otherwise secured thereto or formed therewith. Each breast-receiving portion preferably comprises a shaped upper hemisphere section 6 and a shaped lower hemisphere section 7. The meeting edges of the cooperating hemisphere sections 6 and 7 are suitably joined together, as by a stitched seam 8, and the same are so cut, that when joined they furnish the substantially concavo-convex formation desired for the full-fashioned breast-receiving portions of the brassière. Joined to the outer margins or sides of the respective breast-receiving portions are the usual back straps or sections 9, which pass around the sides of the wearer's torso to encircle the latter 20 and to meet at the back thereof. Preferably the free meeting extremities of said back straps or sections 9 are provided with cooperative separable fastener means (not shown) for joining the same together in the customary manner so as 30 to hold the brassière in place on and about the wearer's body. One or both of said back straps or sections 9 may include an elastic section to assure the desired tight encircling fit of the brassière, as is well understood in the art. 35

Provided in connection with the interior face of the lower hemisphere section 7 of each breast-receiving portion of the brassière, is a lining member or panel 10 of suitable textile fabric, the same corresponding in peripheral shape substantially to that of said lower hemisphere section, and being stitched or otherwise secured by its margins to the latter, except that a portion of the upper margin thereof is cutaway, as at 40 11, so as to be free and thereby form a mouth 45 opening 12 of reduced width leading inwardly into a receiving pocket 13 formed intermediate said lower hemisphere section 7 and said lining member or panel 10. This pocket is adapted to receive and hold the novel uplifting and supporting means involved in this invention. 50

The uplifting and supporting means adapted to be cooperatively related to the lower hemisphere section of each breast-receiving portion of the brassière, comprises a comparatively thin sheet 14 55

of relatively rigid but flexible pyroxylin material or any other material adapted to provide the desired flexible characteristics. This sheet 14 is formed with an outwardly bowed or curved lower peripheral margin 15 and an inwardly bowed or curved upper peripheral margin 16 and with rounded or more or less semi-circular inner end margins 17 and outer end margins 18. Preferably the outer end portions defined by the ends margins 18 are somewhat larger than the inner end portions defined by the end margins 17.

Before the wearer dons the brassière, an uplifting and supporting sheet 14 is inserted endwise through the mouth opening 12 and then turned 15 into position within the pocket 13 contiguous to the lower hemisphere section of each breast-receiving portion; said sheets 14 being preferably disposed with their smaller end portions toward the intermediate panel or diaphragm section 5 20 of the brassière. When the sheets 14 are thus operatively disposed in the pockets 13, their lower outwardly curved margins 15 will generally conform to the curved shape of the bottom of the brassière breast-receiving portions, while the upper 25 inwardly curved margins 16 will extend across the upper parts of the lower hemisphere sections 7 contiguous to the curved mouths of the pockets 13 formed therewith, thereby being positioned to properly engage the wearer's breasts when the 30 brassière is put on.

The usual shoulder straps 19 are provided to extend from the peaks of the upper hemisphere sections 6 of the breast-receiving portions back to the back straps or sections 8 of the brassière in 35 the customary manner.

In applying the brassière, the wearer's breasts are inserted in the breast-receiving portions, with the arms extended through the loops of the shoulder straps 19, so that the latter extend over the 40 wearer's shoulders in the usual manner. As the back straps or sections 8 are passed around the sides of the body and joined together, the lower hemisphere-sections 7 of the breast receiving portions are thereby drawn snugly and tightly 45 beneath the under sides of the wearer's breasts, whereby the uplifting and supporting sheets 14 within the pockets thereof are flexed transversely from end to end, thereby lifting the breasts upward and projecting the same forward within 50 the confines of the breast-receiving portions of the brassière. In this manner the breasts are not only uplifted, but are at the same time molded into the desired rounded and projecting contours desired. Inasmuch as the uplifting and supporting sheets 14 are flexed transversely, such curvature thereof stiffens the same against bending or yielding in the directions of their vertical axes, and consequently a firm support of the breast is 55 assumed against any displacement from the uplifted and molded condition imparted thereto. Owing to the fact that the uplifting and supporting sheets 14 are not in immovably fastened relation to the lower hemisphere sections 7 of the breast-supporting portions of the brassière, but 60 are more or less floatingly carried in the pockets 13 of these parts, the same will be self-adjusting to the most effective functional relation to the shifting under stress of body bending movements of the wearer as to prevent any undue digging or 65 thrusting into the wearer's flesh, thus avoiding all discomfort attendant upon such action, which would occur were the sheets 14 immovably affixed to the breast-receiving portions of the brassière.

In addition to the functional advantages mentioned consequent upon the free floating support 70

of the uplifting and supporting sheets 14 in connection with the brassière, there is the additional advantage that the same are removably related to the latter, and consequently may be quickly and easily removed from the brassière as occasion requires laundering and ironing of the latter.

I am aware that various changes could be made in the above-described constructions, and that widely different embodiments of this invention could be made without departing from the scope 10 thereof. It is therefore intended that all matter contained in the above description and shown in the accompanying drawing shall be interpreted as illustrative and not in a limiting sense.

I claim:—

1. A brassière having breast-receiving portions provided with pockets at and contiguous to the interior faces of the lower hemisphere sections thereof, said pockets having upwardly open mouths, and a transversely elongated sheet of relatively rigid initially flat but flexible material removably disposed within each pocket capable of flexing transversely about the undersides only of the wearer's breasts and thus being stiffened vertically with uplifting, supporting and molding effect upon the latter, and the mouths of said pockets being of a length substantially less than the lateral extension of the pockets whereby the inserted sheets are disposed in enclosed lateral end sections of the pockets and thus retained against escape, the pocket interiors being somewhat larger in area than the inserted sheets whereby the latter are floatingly sustained for self-adjustment to the wearer's body under body moving stresses.

2. A brassière having breast-receiving portions provided with upwardly open pockets at and contiguous to the interior faces of the lower hemisphere sections thereof, and a transversely elongated sheet of initially flat relatively rigid but flexible material removably disposed within each pocket capable of flexing transversely about the undersides only of the wearer's breasts and thus being stiffened vertically with uplifting, supporting and molding effect upon the latter, said sheets having concave curvilinear upper peripheries and rounded ends, said upper peripheries being spaced in use below the nipples of the wearer's breasts, and the mouths of said pockets being of a length substantially less than the lateral extension of the pockets whereby the inserted sheets are disposed in enclosed lateral end sections of the pockets and thus retained against escape, the pocket interiors being somewhat larger in area than the inserted sheets whereby the latter are floatingly sustained for self-adjustment to the wearer's body under body moving stresses.

3. A brassière having breast-receiving portions provided with pockets at and contiguous to the interior faces of the lower hemisphere sections thereof, said pockets having upwardly open mouths adjacent to the medial area of said breast-receiving portions, and a removable sheet of relatively rigid but flexible pyroxylin or like material enterable through said mouths to lie floatingly in transverse extension within each of said pockets, said sheets having outwardly bowed lower peripheral margins, inwardly bowed upper peripheral margins and rounded substantially semi-circular end portions.

4. A brassière having breast-receiving portions provided with pockets at and contiguous to the interior faces of the lower hemisphere sections thereof and extending from side to side of these

sections, said pockets having at their upper transverse ends open mouths of widths less than the widths of said pockets, and a removable initially flat sheet of relatively rigid but flexible material enterable through said mouths to lie within each of said pockets, said sheets, when in position within said pockets, being capable of flexing transversely and being thus stiffened vertically, when

the brassière is applied to the wearer's person, with uplifting, supporting and molding effect upon the wearer's breasts, said sheets having outwardly bowed lower peripheral margins, inwardly bowed upper peripheral margins and rounded substantially semi-circular end portions. 5

JOHN V. HOLLAR.
